UNITED STATES PATENT OFFICE

98,564

DESIGN FOR A CANDLELIGHT OR SIMILAR ARTICLE

Joseph Zeitlin, New York, N. Y.

Application May 17, 1935, Serial No. 56,878

Term of patent 7 years

To all whom it may concern:

Be it known that Joseph Zeitlin, a citizen of the United States and resident of New York city, in the county of New York and State of New York, has invented a new, original, and ornamental Design for a Candlelight or Similar Article, of which the following is a specification, reference being had to the accompanying drawing, forming part thereof, in which, Figure 1 is a front elevational view of the candlelight showing my new design. Figure 2 is a top plan view thereof, and Figure 3 is a perspective view thereof showing the cover raised.

I claim:

The ornamental design for a candlelight or similar article, as shown.

JOSEPH ZEITLIN.
